OIL BURNER SUPPORT

Joseph J. Hurwitz, Brookline, Mass.

Application August 5, 1936, Serial No. 94,381

2 Claims. (Cl. 126—24)

My invention relates to oil burners and means for installing the same primarily for domestic use for heating and cooking.

The chief object of my invention is to provide means for mounting the ordinary household oil burner commonly installed in a cabinet or on the grate of a kitchen range so as to insure safety from fire and to support the burner so that its vertical axis automatically assumes an exactly perpendicular line at all times when in use.

It is well known that means have been employed to install oil burners so that the axis will maintain a fixed perpendicular line consisting of adjusting devices for leveling the surface of the support or stand on which the burner rests, and employing fluid levels on the same for guiding the eye of the operator when installing the burner. Any inclination of the axis of the burner from a perpendicular line when in use tends to cause the flame to smoke and to diminish the amount of heat generated.

In the accompanying drawings illustrating my invention I have shown the same embodied in a structure with a pair of burners. It is evident that it may be employed likewise with a single burner. Fig. 1 is a front elevation of the burners installed in a cabinet with a portion of the cabinet wall removed; Fig. 2 is a plan view of a detail of the invention on line 2—2 of Fig. 1; Fig. 3 is a plan view of the burners and the frame for supporting the same; Fig. 4 is an enlarged front elevation of the burners and the tubular connections with the source of oil supply, and Fig. 5 is an end elevation of my device.

Referring to the drawings, 6 and 7 are oil burners of common form each of which is composed of four perforated cylinders a, b, c, d, concentrically arranged and resting upon the base 8. 9 is an oblong ring having a pin 10 secured to each end and pivoted in the hole 11 in the apex of each of the inverted V shaped legs 12 upon which the ring 9 is supported. These pins are offset upwardly from the ring as clearly shown in Fig. 3 in order that the ring may hang level when the burner bases are assembled therein after the burners have been removed for cleaning and it is desired to put the parts back in place. The base 8 of each of the burners has two upwardly extending arms 13 secured thereto on opposite sides of the burner each having a pin 14 secured to its upper end and extending outwardly into a hole in the ring 9. It is apparent that the burners are free to swing longitudinally of the ring and independently thereof,

and to swing laterally with the pivotal movement of the ring itself.

The burner has the usual cast iron circular base with concentric flanges a, b, c, d, around which the cylinders are disposed and snugly fit, providing a space for one wick between the flanges a and b, and for another wick between c and d. 24 is the cup in the base of the burner into which the oil is delivered and from which it is distributed to the wicks through the channels 24^a, 24^b, and 24^c. 15 is the usual receptacle for the oil mounted and spaced apart from the cabinet 16. The cabinet 16 has the usual apertures 17 for the radiation of the heat. The oil supply pipe 18 terminates in a box 19 from which a flexible tube 20 leads to the burner 6 and another flexible tube 21 leads to the burner 7. The coupling of the flexible tube 20, which may be of any suitable form, is provided with a cock 22, and the coupling of the flexible tube 21 is provided with a cock 23. By means of the cocks 22 and 23 the flow of oil to either or both burners may be regulated and controlled.

An important feature of my invention resides in the employment of the flexible tubes 20 and 21 made of pliable material not readily deteriorated by the mechanical action of the kinds of oil ordinarily used in such burners. Each flexible tube 20 and 21 is laid with considerable slack so that no restraint will be exerted by the tube against the tendency of the burner to swing on its pivots in either direction. Any well known form of coupling may be used for connecting the tubes 20 and 21 to the box 19, and to the burners.

In the above described structure the burner is mounted so as freely to swing and automatically adjust its axis to a perpendicular line in response to a change of position of its supporting frame, and is combined with a source of oil supply spaced apart from the burner and connected thereto by pliable means for conducting the oil. It results in a safe, clean and efficient installation.

What I claim and desire to secure by Letters Patent is:

1. An oil burner support including a pair of inverted V-shaped frames arranged parallel to each other and having aligned bearing openings in their upper ends, a ring frame between the upper ends of said pair of frames and having oppositely disposed aligned upwardly offset journals fitting in said bearing openings, said ring frame having a pair of bearing openings aligned with each other and at right angles to the axis of the first mentioned bearing openings, a burner

base having a pair of oppositely disposed up-standing arms, and journal pins carried by said arms and engaging in the bearing openings of the ring frame.

5. 2. An oil burner support including a pair of inverted V-shaped frames arranged parallel to each other and having aligned bearing openings in their upper ends, a ring frame between the upper ends of said pair of frames and having 10 oppositely disposed aligned upwardly offset journals fitting in said bearing openings, said ring frame having a pair of bearing openings aligned

with each other and at right angles to the axis of the first mentioned bearing openings, a burner base having a pair of oppositely disposed up-standing arms, journal pins carried by said arms and engaging in the bearing openings of the ring frame, a main casing having a bottom whereon 5 said pair of frames is mounted, said casing also having a side wall, a fuel valve carried by said side wall, a burner supported by said base, and a flexible connection between said valve and 10 burner.

JOSEPH J. HURWITZ.
